UNITED STATES PATENT OFFICE.

THOMAS A. WATTS, OF SPRINGFIELD, OHIO, ASSIGNOR TO THE SPRINGFIELD METALLIC CASKET COMPANY, OF SPRINGFIELD, OHIO, A CORPORATION OF OHIO.

SUPPORTING-BRACE FOR COVERS.

1,378,298.

Specification of Letters Patent. Patented May 17, 1921.

Application filed January 10, 1921. Serial No. 436,264.

To all whom it may concern:

Be it known that I, THOMAS A. WATTS, a citizen of the United States, residing at Springfield, in the county of Clark and 5 State of Ohio, have invented certain new and useful Improvements in Supporting-Braces for Covers, of which the following is a specification.

This invention relates to improvements in 10 braces for lids, it being more particularly intended to brace and hold in open position the top of a burial casket.

The object of my invention is to provide a brace which may be readily and quickly 15 released to permit the closing of the top, and which, when the top is raised, will automatically engage a supporting part on the casket body.

In the accompanying drawings:—

20 Figure 1 is an end view of a casket or other container showing the lid in open position with my improved brace applied thereto.

Fig. 2 is a similar view in enlarged form 25 and partly broken away and shown in section.

Fig. 3 is a view of the inner side of the lower end of the brace showing the releasing finger of the same in the position it 30 assumes to permit the brace to be engaged by the holding part on the body.

Fig. 4 is also a view of the inner side of the brace showing the releasing finger thrown to a position to disengage the brace 35 from the holding part.

Fig. 5 is a top plan view of the lower part of the brace and the releasing finger.

Referring to the drawings, 1 represents 40 one of the end walls of the body of the casket or other structure to which my invention is applied, and 2 the top or lid. The brace is represented at 3 and has its upper end pivoted as at 4 in a suitably formed elongated recess 2^a in the lid. The 45 lower end of the brace rests in a pocket 5 formed in the upper edge of the end wall of the body. The under edge of the brace 3 has, near the lower end thereof, a recess 6 to engage a pin 7 which extends across 50 the pocket 5 near the inner end thereof for the purpose of holding the top in its raised position.

As the cover is raised, the slotted portion of the brace automatically drops over this 55 pin 7 and in order to release the brace there-

from when it is desired to lower the cover I have devised the following construction: Pivoted to the extreme lower end of the brace as at 8 is a lever 9, one end of which is provided with a laterally-extending lip 60 10 which overlies the top edge of the brace; the brace, coincident with the lip, being provided with a recess 11 to permit the insertion of a finger of the operator beneath the lip to raise the lever 9 for the purpose to 65 be described. The lower edge of the lever 9 is provided with a beveled surface 12, which, when the lever is raised, engages the pin 7 and cams or lifts the brace away from the pin 7 to release it therefrom, as shown in 70 Fig. 4. The extreme lower end of the lever 9 is formed with another angularly-extending face 13, which, when the lever is lifted to the position shown in Fig. 4 will temporarily rest upon the pin. So soon as the 75 lid begins to lower, however, this face 13 will ride off of the pin, permitting the brace to drop upon the bottom 5^a of the pocket 5 and during the lowering movement of the cover the face 13 will ride along the bottom 5^a, holding the lever 9 in the position shown in Fig. 4. Near the limit of the lowering movement of the cover, the lever 9 will contact the over-hanging portion 5^b 80 near the outer end of the pocket and return 85 the lever 9 to the position shown in Fig. 3 so as to uncover the recess 6 so that it will be free to again engage the pin 7 upon the next raising movement of the cover.

The extreme outer end of the lever is also 90 provided with a laterally-extending lip 14, which when the lever is raised, engages the end of the brace and forms a stop.

In ordinary practice, one of these braces 95 will be provided at each end of the cover and, by the construction described, it will be seen that when the operator releases one brace from its corresponding pin, it will be held in released position while the brace at the opposite end of the structure is being 100 released. This arrangement also provides a very simple arrangement which is economical in manufacture and effective for the purpose for which it is intended.

Having thus described my invention, I 105 claim:—

1. In a structure of the character described, the combination, with a body and a cover, of a brace pivotally connected to the cover and having its lower end extended 110

into a pocket in the body, the lower end of the brace having a recess, a projection in said pocket to engage said recess, and a cam lever pivoted to the lower end of said brace to engage said projection to lift the brace therefrom.

2. In a structure of the character described, the combination, with a body and a cover, of a brace pivotally connected to the cover and having its lower end extended into a pocket in the body, the lower end of said brace having a recess, a projection in said pocket to coöperate with said recess, and a cam lever pivoted to the lower end of said brace to engage said projection to lift the brace therefrom, the end of said cam lever having a lateral projection which in the raised position of the cover lies on the upper edge of the brace.
3. In a structure of the character described, the combination, with a body and a cover, of a brace pivotally connected to the cover and having its lower end extended into a pocket in the body, the lower end of the brace having a recess, a projection in said pocket to coöperate with said recess, and a lever pivoted to the lower end of said

brace having a cam surface to engage said projection to lift the brace therefrom, said cam lever being also provided with an angular face to engage the bottom of the pocket and ride thereon during the lowering movement of the cover.

4. In a structure of the character described, the combination, with a body and a cover, of a brace pivotally connected to the cover and having its lower end extended into a pocket in the body, the lower end of the brace having a recess, a projection in said pocket to coöperate with said recess, a cam lever pivoted to the lower end of said brace adapted when raised to engage said projection and lift the brace therefrom, together with means for holding said cam lever in its raised position during the lowering movement of the cover, and a projecting part at the outer end of the pocket to engage said lever to restore it to its former position.

In testimony wherof, I have hereunto set my hand this 4th day of January 1921.

THOMAS A. WATTS.
